Des. 215,270
Patented Sept. 23, 1969

215,270

WAFER TRAY

Henry W. Gutsche, St. Louis, Darrell M. Harris, Kirkwood, and Robert J. Walsh, Ballwin, Mo., assignors to Monsanto Company, St. Louis, Mo., a corporation of Delaware

Filed May 21, 1968, Ser. No. 12,021

Term of patent 14 years

Int. Cl. D9—04

U.S. Cl. D9—187

FIG. 1

FIG. 2

FIG. 3

FIG. 4

FIG. 5

FIG. 6

FIGURE 1 is a top perspective view of a wafer tray showing our new design;

FIGURE 2 is a top plan view of the wafer tray of FIGURE 1;

FIGURE 3 is a front elevational view of the wafer tray of FIGURE 1, the rear elevational view being a mirror image thereof;

FIGURE 4 is a bottom plan view of the wafer tray of FIGURE 1;

FIGURE 5 is a right end elevational view of the wafer tray of FIGURE 1; and

FIGURE 6 is a left end elevational view of the wafer tray of FIGURE 1.

We claim:

The ornamental design for a wafer tray, as shown.
